UNITED STATES PATENT OFFICE.

HENRY S. LOCKWOOD, OF SOUTH NORWALK, CONNECTICUT, ASSIGNOR TO
THE LOCKWOOD MANUFACTURING COMPANY, OF SAME PLACE.

DESIGN FOR A TOY BANK.

SPECIFICATION forming part of Design No. 13,261, dated August 22, 1882.

Application filed June 23, 1882. Term of patent 7 years.

To all whom it may concern:

Be it known that I, HENRY S. LOCKWOOD, of South Norwalk, in the county of Fairfield and State of Connecticut, have invented a new and Improved Design for Toy Banks, of which the following is a full, clear, and exact description.

Reference is to be had to the accompanying drawing, in which a perspective view of my newly-designed toy bank is shown.

The design consists in a rabbit standing or resting on its hind legs and eating an apple or other fruit, which it holds between the front legs or paws. The fruit is provided with a slot, through which coins can be dropped into the hollow rabbit, which thus serves as a toy bank. The ears of the rabbit are pivoted so

that they can be swung forward, as shown in dotted lines, and the rabbit's tail is also pivoted and can be swung. The rabbit's ears, the fruit the rabbit is holding, and the base on which the rabbit rests can be made more or less ornamental, as may be desired.

Having thus described my invention, I claim as new and desire to secure by Letters Patent—

The herein-described design for toy savings-banks, consisting of a rabbit standing on its hind legs and holding a fruit between its front legs or paws, as set forth.

HENRY S. LOCKWOOD.
